TONGUE SCRAPER

Garland D. Runnels, New York, N. Y.

Application October 9, 1947, Serial No. 778,842

2 Claims. (Cl. 128—304)

1

My present invention relates to an improved construction of scraper intended for use in the mouth.

For sometime it has been recognized that better general health through better mouth hygiene is obtained by keeping the tongue free of the coating which tends to, and from time to time does accumulate thereon, usually because of one or more internal disorders. Furthermore, a clear tongue affords greater taste enjoyment of the food and drink taken into the body through the mouth. I have heretofore obtained United States Letters Patent No. 2,218,072, issued October 15, 1940, on one form of scraper for clearing the tongue of such coating.

In the device of that patent a rigid handle carries a rigid reinforcement for a resilient rubber head and the face of the head is provided with various scraping, scrubbing and guard ridges. While that device functions satisfactorily, it has been found that the usefulness of such a device can be increased and the construction thereof considerably simplified, and these are among the principal objects of the present invention.

Other objects are to provide an improved construction of handle which will insure the proper and most efficient use of the scraping and scrubbing head, and which will further protect against accidental misuse of the device to exert too great a pressure whereby to possibly bruise, pinch or otherwise temporarily harm the tongue.

A further object of the present invention is to provide a construction of head which is also an efficient scraper and scrubber even though used with diagonally or laterally directed strokes, thereby giving greater freedom of use.

These and other objects of my present invention will be apparent from this specification taken in conjunction with the accompanying drawings, in which—

Figure 1 is a front elevational view of my improved device.

Fig. 2 is a side elevation of the device of Fig. 1.

Fig. 3 is a cross-section on the line 3—3 of Fig. 2.

Fig. 4 is a cross-section on the line 4—4 of Fig. 2.

While my invention further resides in the combination, construction and arrangement of parts illustrated in the accompanying drawings, I have shown therein, for illustrative purposes, only a preferred embodiment, and wish it understood that the same is susceptible of modification and change without departing from the spirit and scope of the invention as set forth in the appended claims.

2

The device comprises a handle 11 and head 12 which are joined by a neck 13, the whole being molded in integral construction, and desirably of any suitable semi-rigid plastic material, such as polyethylene, which material may be generally described as a polymerized hydrocarbon.

In side view, the handle, neck and head have a single plane, flat back 14, as seen in Fig. 2. In front elevation, the handle 11 has substantially parallel side edges, which edges taper inwardly into the reduced neck 13, as seen in Fig. 1. The handle also has a tapered reinforcing rib 15 integral with the handle and extending along a major portion of the length of the handle. The rib 15 is narrow in cross section (Fig. 4) and projects a substantial distance from the front face of the handle. As seen in Fig. 2, this rib also tapers into the reduced neck 13. In addition to its reinforcing function, the rib 15 greatly improves the action of the handle when gripped in the fingers of the hand in use.

The head 12 is somewhat elliptical in shape, being of greater width than the handle, and the side and front surfaces of this head also taper into the reduced neck 13. The front face of the head is provided with laterally extending upstanding ridges 21 and 22 respectively located at opposite ends of the head, and these are joined together by upstanding ridges 23 and 24 that respectively extend along each side edge of the head. The hollow space which is defined by the ridges 21 to 24, inclusive, is divided into a series of small pockets 25 and 26 respectively formed by means of a cross rib 27 and a plurality of cross ribs 28. The end ridges 21 and 22 and the cross rib 27 are of uniform height and define the maximum thickness of the head. The side ridges 23 and 24 are slightly less in height than ridges 21 and 22, the difference being of the order of one-thirty-secondth of an inch. Each of the ridges 21 to 24, inclusive, and the cross rib 27 have flat top and side surfaces providing relatively sharp corner edges. Each of the cross ribs 28 has an inclined surface 28a and a flat side surface 28b

45 meeting in a comparatively sharp corner 29, with the taper extending from such corner to the juncture of the side of the next adjacent rib 28 and the bottom of the corresponding pocket 26. The corners 29 protrude approximately to the level of the flat ribs 21, 22 and 27, which is slightly above the level of the tops of the side ridges 23 and 24, and where this occurs the corner portions 29 of the cross ribs 28 are extended outwardly, as seen at 31, so as to overlie the side ridges 23 and 24.

As noted above, all surfaces taper into the re-

duced neck 13, and at its smallest diameter, indicated at 32, in Fig. 3, the neck 13 is substantially round in cross section, and free of all areas in the nature of a rib, which construction is provided to permit the handle to assume different angular positions with respect to the plane of the head, at the convenience of the user. That is to say, the construction of the head and handle will not permit ready bending thereof whereas the construction of neck 13 permits flexing of the handle with respect to the head. Most often, the handle will be bent in the direction indicated by the dash lines 33 in Fig. 2, the pivot occurring about the neck 13.

In use, the handle of the device is held in the hand and the head 12 is placed on the tongue of the user with the front surfaces of the various ribs and ridges next to the tongue. Then, by moving the head back and forth over the tongue while exerting a slight downward pressure the edges of the ribs and ridges will loosen and remove any extraneous coating thereon. By reason of the arrangement permitting the flexing of the handle about the neck 13, it is highly improbable that any undue pressure will be exerted on the tongue. Furthermore, the flexing of the handle allows the face of the head to remain flat against the tongue as it is moved over the surfaces near the root thereof. By reason of the relative heights of the lateral ribs and ridges to the side ridges, the downward pressure on the head causes the side ridges to engage the tongue and become effective in removing the coating, especially when the head describes angular paths as it is moved back and forth and the relative positions of the tongue and head are changed. These side ridges will be effective also if the head is moved from side to side.

The pockets 25 and 26 will hold and distribute any mouth wash or other preparation used for the purpose of facilitating removal of the coating and for other purposes, and particles of the extraneous coating will collect in these pockets as the head is withdrawn from the mouth. The construction allows for readily washing the head free of these particles and generally cleaning the head by holding the same under a faucet.

I claim:

1. An applicator for the tongue comprising a

handle, a head connected to said handle, a plurality of lateral ridges on the front face of said head, ridges extending along each side of said head and defining a plurality of pockets with said lateral ridges, and a resilient neck portion between the head and the handle, said neck portion being substantially round in cross-section whereby the handle is permitted to assume different angular positions in all directions with respect to the plane of the head.

2. An applicator for the tongue comprising a handle, a head connected to said handle, marginal end and side ridges on the front face of said head, said ridges having flat outer surfaces and substantially straight side surfaces, a plurality of cross-ribs extending between said side ridges and defining a plurality of pockets with said side ridges, at least some of said ribs having an inclined upper surface and a flat surface meeting in a substantially sharp edge, the sharp edges of said ribs and the flat surface of said end ridges terminating in substantially a common plane, and the side ridges terminating substantially in said common plane, all of said surfaces being effective to engage the tongue as said head is moved over the tongue in various directions, and a resilient neck portion between said head and said handle, said neck portion being substantially round in cross-section whereby the handle is permitted to assume different angular positions in all directions with respect to the plane of the head when pressure is exerted on the head and handle.
